W. J. FLOWERS

ROPE AND CABLE TIE

Filed March 27, 1922

FIG. 1.

FIG. 3.

FIG. 2.

W. J. FLOWERS, INVENTOR.

BY *Monroe E. Miller*
ATTORNEY.

UNITED STATES PATENT OFFICE.

WILLIAM JAMES FLOWERS, OF COMPLETE, MISSISSIPPI.

ROPE AND CABLE TIE.

Application filed March 27, 1922. Serial No. 547,096.

To all whom it may concern:

Be it known that I, WILLIAM J. FLOWERS, a citizen of United States, residing at Complete, in the county of Lauderdale and State 5 of Mississippi, have invented certain new and useful Improvements in Rope and Cable Ties, of which the following is a specification, reference being had therein to the accompanying drawing.

10 The present invention relates to devices for tying or fastening ropes, cables and the like, and it is the object of the invention to provide an extremely simple and inexpensive device of that kind which is also practical 15 and efficient for the intended purposes.

Another object is the provision of such a device which can be easily and cheaply made from a single piece or blank of sheet metal or similar material.

20 A further object is to provide such a device having novel means for receiving the rope or cable and binding or fastening same securely.

With the foregoing and other objects in 25 view, which will be apparent when the invention is more fully understood from the description, the invention resides in the construction and formation of the device as hereinafter described, it being understood that 30 changes can be made within the scope of what is hereinafter claimed, without departing from the spirit of the invention.

The invention is illustrated in the accompanying drawing, wherein—

35 Figure 1 is a plan view of the device showing the rope or cable fastened therein.

Fig. 2 is a side elevation of the device.

Fig. 3 is an end view of the device, looking from the top downward in Fig. 1.

40 The device is formed from a square piece or blank of sheet metal or similar stock, which is bent into U-shaped cross-section, to provide a channel-shaped member having the sides 4 and bend 5, with a channel or 45 groove between said sides along the bend, in which the rope or cable can lay. Each side 4 is provided with a slot 6 extending from one end, and the two slots are located at opposite ends of said sides. Said slots 50 extend at an angle from the ends of the sides 4 toward the bend 5, and decrease in width

from their open to their closed ends, as seen in Fig. 2. The closed or inner ends of the slots are in overlapping relation, as seen in Fig. 2, and said slots are also arranged at 55 acute angles with the bend or intermediate portion 5 of the plate or member constituting the device.

The device may be used for many different purposes, such as for fastening the guy 60 ropes of tents and the like, hammock ropes, etc. The chief use of the device is for fastening the terminal portion of the rope or cable after it is doubled back to form a loop. Thus, as shown in Fig. 1, the cable or rope 65 7 has one terminal portion doubled back to form the loop 8 to engage a stake, or other anchor member, and the device is then placed on the cable or rope 7, so that said rope or cable lays in the channel or groove against 70 the bend 5. The free terminal portion of the rope is then drawn into the slot 6 opening opposite to the loop 8, as at 9, and after the rope is pulled tightly into such slot 6, it is passed across the portion of the rope which 75 lays against the bend 5, as at 10, and the terminal portion of the rope is then drawn into the other slot 6, as at 11, and is pulled tight. Due to the fact that the slots 6 converge, the portion 10 of the rope which 80 extends across the longitudinal portion laying against the bend 5, will be pulled toward a transverse position when the terminal is pulled tight. Furthermore, the rope being pulled into the slots 6, which decrease in 85 width, will be given a wedge fit in said slots, for gripping or clamping the rope in said slots, and, in addition, the rope in being pulled into the slots will be forced by cam action toward the bend 5, thereby clamping 90 the rope 7 between the portion 10 and bend 5. As a result, the terminal portion of the rope is tightly secured in place, and there are several factors which will prevent the rope from slipping. First, the rope has a double 95 bend where it passes through the slots 6, to prevent slipping. Second, the rope being drawn into the tapered slots 6 will bind in said slots by a wedging action. Third, the rope being moved by cam action in said slots 100 due to the pull on the rope, will create a clamping action. Therefore, although the

device enables the terminal portion of the rope to be readily fastened to the main portion, there is no danger of slippage, and the greater the pull on the rope, the tighter it 5 will be held.

Having thus described the invention, what is claimed as new is:—

1. A device of the character described comprising a portion along which a portion of a 10 rope can lay, and having slots opening in different directions for receiving the terminal portion of the rope to extend across the aforesaid portion of the rope and the slots being so arranged that a pull on said terminal portion of the rope will clamp the first 15 named portion of the rope between said terminal portion and said portion of the device.

2. A device of the character described having a portion along which a portion of a rope 20 can lay, and having a pair of slots opening in different directions for receiving the terminal portion of the rope to extend across the aforesaid portion of the rope, and so arranged that a pull on said terminal portion 25 of the rope will clamp the first named portion of the rope between said terminal portion and said portion of the device, said slots decreasing in width for binding the terminal portion of the rope therein.

3. A device of the character described having a portion along which a portion of a rope 30 can extend, and having slots opening in different directions for receiving the terminal portion of the rope to extend across the aforesaid portion of the rope, said slots being 35 arranged at acute angles with said portion of the device for clamping the first-named portion of the rope between the terminal portion and said portion of the device when 40 said terminal portion is pulled.

4. A device of the character described having a portion along which a portion of a rope can extend, and having slots opening in different directions for receiving the terminal portion of the rope to extend across the aforesaid portion of the rope, said slots being 45 arranged at acute angles with said portion of the device for clamping the first-named portion of the rope between the terminal portion and said portion of the device when said terminal portion is pulled, and said slots decreasing in width for binding the terminal portion of the rope therein.

5. A device of the character described 55 comprising a member of U-shaped section having sides with slots therein for receiving the terminal portion of a rope to extend across a portion of the rope lying against the bend of said member and so arranged 60 that a pull on the terminal portion of the rope will clamp the second-named portion of the rope between said terminal portion and bend of said member.

6. A device of the character described 65 comprising a member of U-shaped section

having sides with slots therein for receiving the terminal portion of a rope to extend across a portion of the rope lying against the bend of said member and so arranged that a pull on the terminal portion of the rope will clamp the second-named portion of the rope between said terminal portion and bend of said member, said slots decreasing in width for binding the terminal portion of the rope therein. 70

7. A device of the character described comprising a member of U-shaped section having sides with slots therein for receiving the terminal portion of a rope to extend across a portion of the rope lying in said member against the bend thereof, said slots being arranged at acute angles with the bend portion of said member for clamping the rope between said terminal portion of the rope and said portion of said member when 80 said terminal portion is pulled. 75

8. A device of the character described comprising a member of U-shaped section having sides with slots therein for receiving the terminal portion of a rope to extend across a portion of the rope lying in said member against the bend thereof, said slots being arranged at acute angles with the bend portion of said member for clamping a rope between said terminal portion of the rope and said portion of said member when 90 said terminal portion is pulled, and said slots decreasing in width for binding the terminal portion of the rope therein. 95

9. A device of the character described comprising a member of U-shaped section having sides with slots opening in different directions for receiving the terminal portion of a rope and so arranged that a pull on the terminal portion of the rope will 100 clamp another portion of the rope between said terminal portion and the bend of said member in which the second-named portion of the rope lays. 105

10. A device of the character described comprising a member of U-shaped section having sides with slots opening in different directions for receiving the terminal portion of a rope and so arranged that a pull on the terminal portion of the rope will 110 clamp another portion of the rope between said terminal portion and the bend of said member in which the second-named portion of the rope lays, said slots decreasing in width for binding the terminal portion of 115 a rope therein. 120

11. A device of the character described comprising a member of U-shaped section having sides with slots opening in different directions for receiving the terminal portion of a rope, said slots being arranged at acute angles with the bend portion of said member so that they force the terminal portion of the rope, when pulled into the slots, by cam action toward said bend portion of 125 130

the member for clamping the rope between said terminal portion and bend portion.

12. A device of the character described comprising a member of U-shaped section having sides with slots opening in different directions for receiving the terminal portion of a rope, said slots being arranged at acute angles with the bend portion of said member so that they force the terminal por-

tion of the rope, when pulled into the slots, 10 by cam action toward said bend portion of the member for clamping the rope between said terminal portion and bend portion, and said slots decreasing in width for binding said terminal portion therein. 15

In testimony whereof I hereunto affix my signature.

WILLIAM JAMES FLOWERS.
